UNITED STATES PATENT OFFICE.

JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK.

PRESS.

Application filed May 2, 1925. Serial No. 27,411.

This invention relates to garment pressing machinery and an object is to produce a press which opens and closes by gravity and the press is worked by any suitable operating means, such for example as motor means.

Another object of the invention is to produce an improved press which opens, closes, and presses by power thereby entirely eliminating undue manual effort on the part of the operator.

A further object of the invention is to produce a safe pressing machine to the extent that the operator is compelled to employ both hands to control the press and to this end the operator necessarily, in using both hands to manipulate the press, is restrained from accidentally getting his hands between the pressing jaws because of the fact that his hands are employed at a point distant to the closing jaws.

In pressing machines of this type it is necessary that the jaws open through a wide movement to expose the lower pressing jaw member, in order to obtain extended visibility of the work and to permit the operator to have sufficient room to work. This requirement of wide opening jaws means that some part of the press, as for example the press lever, must move through a long distance of travel. It is undesirable because of waste of energy to provide a long stroke motive power means as for example a steam motor so it becomes desirable to operate the press through a long distance of travel by a power unit having a short stroke. To fulfill these conditions an improved disconnecting device is employed to connect and disconnect the power unit with the press lever at the proper period of operation and this is one of the features of the invention.

The accompanying drawings illustrate a preferred form of the invention serving to disclose the construction, principle, and mode of operation thereof and ordinary changes may be made without departing from the scope of the invention.

Figure 1 shows a side view of the press in closed position under pressure of the fluid power unit and the fragmentary dotted line parts illustrate the press lever in uplifted position to raise the press head. This view is a partial sectional view taken on the line 1—1 of Figure 3.

Figure 2 illustrates a side fragmentary view of the press showing the press lever open or up in full line position and closed or down in dotted line position but without pressure being applied thereto.

Figure 3 illustrates a rear view of the press in closed position under pressure.

Referring now more particularly to the drawings for a further description of the invention, there is shown a pressing machine frame 10 which usually supports a fixed pressing member as a buck or jaw 11. A press head or jaw 12 is adapted to be raised and lowered through a long distance of travel in relation to the lower jaw 11 and the pressing jaws are suitably heated by any appropriate means, steam generally being used as is well known. A press lever is pivoted at 14 on the frame 10 and the rear end of this lever is preferably turned downwardly in a vertical plane to work in close relation to the frame and the lever is provided on the lower end with a thrust pad 15 against which a power device coacts to produce high final pressure.

A suitable fluid pressure motor, or a diaphragm or sylphon fluid actuated motor 17 is mounted on the frame and may be enclosed by a casing 18. The sylphon or diaphragm 17 is adapted to contract and expand under the influence of fluid pressure as steam injected thereinto and exhausted therefrom. The lower end of the sylphon connects with a steam supply pipe line 19 which conveys steam to the power unit and exhausts its therefrom. A three-way valve 20 connects the pipe 19 with a steam supply pipe 21 which is adapted to be connected with a boiler to feed to the sylphon and an exhaust pipe 22 also connects with the three-way valve 20. One position of the three-way valve 20 admits steam from the pipe 21 and boiler into the pipe 19 to expand the sylphon while another position of the valve 20 closes the pipe 21 and simultaneously connects pipes 22 and 19 in order that the steam be exhausted from the sylphon out through the pipe 22 at the end of the pressing operation.

In order to render the operation of the press perfectly safe, another steam valve 24 is included in the pipe 21 and merely provides a cut-off in the pipe 21 between the boiler and the three-way valve 20. Both valves 20 and 24 are equipped with control

rods 25 which connect with manual control handles 26 and 27. It is to be observed that the operator must necessarily operate both handles 26 and 27 to gain complete control of the admission and exhaust of steam to and from the sylphon. The two handles 26 and 27 are spread apart a suitable distance in order that the operator cannot possibly work both handles with one hand and so he is compelled to grasp one handle with one hand and the other handle with the other hand.

- 10 When the operator desires to expand the sylphon 17, he grasps both handles 26 and 27 and opens both valves 20, and 24 which are held normally closed by means not shown, so that steam flows into the sylphon to close the press and produce pressure. At the end of the pressing operation the operator similarly grasps both handles 26 and 27 to close the
- 15 valve 24 whereby the flow of steam is stopped from the boiler and to reset the valve 20 in order that the exhaust pipe 22 be brought in communication to the pipe 19 thereby permitting the steam under pressure to exhaust to atmosphere or to a condenser. Any suitable spring closed valves 20 and 24 may be used.
- 20
- 25

The sylphon is equipped with a plunger rod 29 which carries a connecting rod 30 which pivotally connects at 31 with a crank shaft cam or abutment device 32. The crank cam device 32 is anchored or keyed on the shaft 33 which is in turn journaled in bearings 34 on the frame or legs 10 of the press.

- 30
  - 35
  - 40
  - 45
  - 50
  - 55
- The reciprocating motion of the plunger 29 serves to rotate the cam 32 and shaft 33 through a limited degree of movement. The cam 32 operates similarly to a crank shaft since its function is to translate motion to the press lever 13 and this crank cam 32 is made with an abutment shoulder 35 which coacts with the lower end 15 of the press lever 13 to exert pressure rearwardly on the lever after the head 12 is closed upon the buck 11. The thrust of the abutment shoulder 35 against the lower end of the press lever is limited to that period of time which ensues after the press head has closed because prior to that time, the said lower end 15 of the press lever swings entirely clear and free of the cam crank shaft device 32. When the sylphon is collapsed or contracted, the connecting rod 30 acts to rotate the part 32 clockwise thereby withdrawing the abutment shoulder 35 from the path of the swinging press lever end 15.

A bell crank comprising arms 38 and 39 is fixed on the shaft 33 and swings as the shaft is turned by the motor means 17. The upper end of the bell crank 38 is fitted with a lug or roller 40 adapted to swing in relation to and in alignment with the lower end of the press lever 13 while the other arm 39 of the bell crank carries a counter balance weight 41 which may be adjusted back and

forth on the arm 39 to balance the head 12 for this weight is provided for that purpose as will be described.

Assuming that as in Figure 1 the work such as a garment between the head and buck 11 is completely pressed and that the press is ready to be opened, the operator now actuates both handles 26 and 27 to exhaust steam from the sylphon 17 to permit it to collapse or contract. This action serves to rotate clockwise the cam crank shaft 32 which removes the abutment shoulder 35 of the cam away from the lever 13 as shown in dotted line position in Figure 2. It follows that the shaft 33 is rotated clockwise which permits the weight 41 to gravitate downwardly thereby hastening a quick exhaust of steam from the steam motor means which simultaneously brings the lug 40 into contact with the rear edge of the press lever 13 whereupon the weight 41 is pressed against the lever 13 to quickly lift the head 12 and hold it in uplifted position under power of the weight 41 as noted in dotted lines in Figure 1 and in full line position in Figure 2.

With the head up as just described, the pressing operation is now carried out by spreading the work upon the lower jaw or buck 11 whereupon the operator actuates both handles 26 and 27 to expand the sylphon which begins to lift the weight 41 which in turn permits the arm 38 to swing counterclockwise thereby retracting the lug 40 from the press lever 13 and the weight of the heavy head 12 immediately gravitates downwardly as fast as the lug 40 moves counterclockwise. Thus a short expansional movement of the sylphon permits the head 12 to travel through a long distance from high lifted position to contacting position on the buck 11. The lower end of the press lever swings rearwardly past the cam shoulder 35 before the shoulder reaches a position in alignment with the press lever.

The considerable weight of the head 12 is imposed upon the work on the buck 11 prior to the inception of the power pressing movement because of the fact that no weight is attached to the press lever at this time to diminish the dead weight of the head. The abutment shoulder 35 now approaches the press lever end 15 and bears against it to produce ultimate pressure between the jaws.

It is now seen that I have produced a press with a movable or swinging jaw support member such as the press lever 13 having a long travel to open and close the press, together with operating means such as the motor means shown having a short stroke or travel, it being desirable to employ a short movement motor means in order that the latter be economical to operate and be simple in construction. The intermediate means or power connecting and disconnecting de-

vice 32 placed between the operating means or motor and swinging member 13 simply acts to connect the motor to the swinging member after the press is closed since only at that time is the full force of the motor required to produce jaw compression and for that function a motor means having a short powerful stroke is preferable.

Also the motor means travels in one direction to lift the counterweight 41 to permit the press to close of its own jaw weight, and travels in the reverse direction to connect the counterweight with the movable jaw to open the press. New and useful results are attained by connecting and disconnecting the counterweight and weight lever 38-39 to and from the movable press jaw, the counterweight being movable independently of the movable press jaw and operating the means such as the arm 38 to engage and disengage the movable jaw support 13 to connect and disconnect the counterweight from the movable jaw. The press therefore opens and closes by gravity, the gravity means being controlled by the operating means 18 in motor form or other suitable form. After the press is closed, the high compression device 32 engages the support 13 to produce jaw compression.

What I claim is:

1. A press comprising, cooperating jaws, a movable jaw support carrying a jaw to open and close the press, said jaw being gravity actuated toward closed position, a counterweight mounted for movement independently of the movable support and jaw; means operated by the counterweight to engage the movable jaw support after the press is closed to open the press by gravity, and means to disengage the counterweight from the support to permit the press to close by gravity; operating means connected with the counterweight for moving the same, and means to engage the movable jaw support after the press is closed and actuated by the operating means to produce jaw compression.

2. A press comprising, cooperating jaws, a movable jaw supporting member carrying a jaw to open and close the press, said jaw being gravity actuated toward closed position, a counterweight normally disconnected from the supporting member and heavier than the movable jaw, means operated by the downward movement of the counterweight to engage the supporting member to open the press by gravity, operating means cooperating with the counterweight to move it upwardly to allow the press to close by gravity, and a device connected with the operating means to engage the supporting member after the press is closed and to exert thereagainst the force of the operating means to produce jaw compression.

3. A press comprising, press jaws, a sup-

port carrying one jaw and movable to open and close the press which tends to remain closed by the weight of said movable jaw, a counterweight movable independently of the support and movable jaw, lever means 70 operated by the counterweight to engage the support and open the press by the counterweight which is heavier than the movable jaw, operating means to lift the counterweight and remove the lever means from 75 the support to allow the press to close by gravity, and a high compression device actuated by the operating means to engage the support after the press closes to produce jaw compression.

4. A press comprising, press jaws, a press lever carrying one jaw to open and close the press, said jaw being gravity actuated toward closed position, a counterweight, a weight lever one end of which carries the 80 counterweight and the other end of which is adapted to engage and swing the press lever to open the press by gravity, operating means to swing the press lever engaging end of the weight lever away from the press 85 lever to permit the press to close by gravity, and means to produce jaw compression.

5. A press comprising, press jaws, a press lever carrying one jaw to open and close the press, a counterweight, a weight lever 90 one end of which carries the counterweight and the other end of which is adapted to engage and swing the press lever to open the press by gravity, operating means to swing the press lever engaging end of the 95 weight lever away from the press lever to permit the press to close by gravity; and a power connecting means movable with the weight lever and actuated by the operating means to engage the press lever after the 100 press closes to effect jaw compression, and which disengages from the press lever before the aforesaid weight arm engages said press lever in order that the counterweight may open the press as aforesaid.

6. A press comprising, press jaws one of which is gravity actuated toward closed position, a press lever to open and close the press and one end of the lever being directed vertically downwardly; a bell crank, a 115 counterweight on one end thereof, and means on the other end to engage the vertical end of the press lever to open the press by action of the counterweight; operating means to swing the bell crank and lift the 120 counterweight against gravity to allow the press to close by gravity, and means to produce jaw compression.

7. A press comprising, press jaws one of which is gravity actuated toward closed position, a press lever to open and close the 125 press and one end of the lever being directed vertically downwardly; a bell crank, a counterweight on one end thereof, and means on the other end to engage the vertical end 130

of the press lever to open the press by action of the counterweight; operating means to swing the bell crank and lift the counterweight against gravity to allow the press to close by gravity, and an abutment device actuated by the operating means to engage the lower end of the press lever after the press closes to produce jaw compression.

8. A press comprising in combination, a frame, cooperating press jaws carried by the frame between which the work is placed, a press lever carrying one of the jaws which swings through a long distance to open the press wide, said press lever having its rear end turned down into the frame to swing within the space of the frame, a weight carrying lever pivoted in the frame with one end thereof adapted to move against the

press lever, a weight on the other end of the weight carrying lever which causes the press to open when the opposite end thereof moves against the press lever as aforesaid, motor means directly connected with the weight carrying lever to lift and move it away from the press lever in order that the press may close by gravity, means connected with the motor means and operable thereby by which the motor is disconnected from the press lever during the press closing gravity operating period, and a device on the last named means by which it connects with the press lever after the press closes to produce final pressure.

In testimony whereof I affix my signature.

JAMES CAMROD LEDBETTER.
